UNITED STATES PATENT OFFICE.

THOMAS HEWTON, OF DUNEDIN, NEW ZEALAND.

APPARATUS FOR STRAINING WIRE.

SPECIFICATION forming part of Letters Patent No. 700,044, dated May 13, 1902.

Application filed July 29, 1901. Serial No. 70,157. (No model.)

To all whom it may concern:

Be it known that I, THOMAS HEWTON, miller, a subject of the King of Great Britain, and a resident of the city of Dunedin, in the British Colony of New Zealand; have invented certain new and useful Improvements in an Apparatus for Stretching or Straining Wire, of which the following, taken in connection with the accompanying drawings, is a specification.

10 The invention aims to construct an apparatus for stretching or straining wire, which is especially adapted for pulling in a quantity of wire, as there is no limit to the amount of wire that can be drawn in.

15 The invention further aims to construct an apparatus for stretching or straining wire which shall be extremely simple in its construction, strong, durable, efficient in its operation, comparatively inexpensive to set up; 20 and to this end it consists of the novel combination and arrangement of parts hereinafter more specifically described, illustrated in the accompanying drawings, and particularly pointed out in the claim hereunto appended.

25 In describing the invention in detail reference is had to the accompanying drawings, forming a part of this specification, wherein like letters of reference indicate corresponding parts throughout the several views, and 30 in which—

Figure 1 is a side elevation of the apparatus in the act of straining or stretching wire where an amount of wire has to be taken up. Fig. 2 is an end elevation of the fixed head 35 as used for taking up long lengths of wire. Fig. 3 is a similar view of the movable head. Fig. 4 is a front elevation, broken away, of a modified form of apparatus, in which the sliding head is moved by a rack and pinion 40 and the employment of a pawl to maintain the desired position. Fig. 5 is a front elevation, partly in section, of a modified form of apparatus, the movable head being pushed instead of pulled.

45 Referring to the drawings by reference-letters, A denotes the main bar of the apparatus and extends in a longitudinal manner and which may be provided throughout its length with the teeth A', or, as shown, the teeth are 50 only provided a portion of the length of the bar A. One end of the bar A is bent up-

wardly or in a vertical manner, as at A⁴, and terminates into a horizontally-extending arm A³, forming a fixed head, having the lower face thereof provided with the grooves A⁵. 55

The reference-letter D' denotes a concentric clip and handle for clipping the wire C, and the reference-letter B denotes an eccentric clip for clipping the other wire E. The clip B is arranged on one side of the vertical portion A⁴ of the bar A, and the clip D' is arranged on the opposite side of the vertical portion A⁴ of the bar A. The clips are pivotally connected to the vertical portion A⁴ of the bar A by means of the pin A⁶. 65

The reference-letter F denotes the movable head, which is constructed of a vertically-extending member, having its lower portion enlarged, as at F', and provided with an opening or slot F² to permit of the sliding of the 70 movable head upon the bar A. The upper wall of the opening or slot F² is toothed, as at F³. The vertical member F or movable head F is further provided at one side with a swell or offset F⁴, having its upper edge 75 grooved, as at F⁵, to receive the wire E. At the top of the vertical member F a clip D is pivoted thereto by means of the pin F⁶. The clip D is arranged above the offset F⁴, so it can engage and clamp the wire in position. 80 The vertical member F is further provided with an opening F⁷ to receive the loop or oval link F⁸, which is adapted to engage the hooked end G² of the operating-lever G. Mounted upon the bar A is an auxiliary sliding head 85 G', which is formed with a slot or opening to permit of the mounting of the head G upon the bar A, and this slot or opening has its top wall suitably toothed for engagement with the teeth of the bar A and which is indicated in 90 dotted lines, Fig. 1. The upper end of the auxiliary head G' is pivoted to the lever G by means of the pin G⁴.

In the modified form of construction shown in Fig. 4 the movable head F² is provided 95 with a pinion F⁹, mounted upon a pin F¹⁰, and further provided with a pawl F¹¹, which is adapted to engage in the rack A¹⁰, the latter forming in this modified construction the main or sliding bar and having teeth H, or, 100 in other words, the main or sliding bar, as shown in Fig. 4, consists of a rack-bar, while

in Fig. 1 the main or sliding bar A has one of its edges provided with ratchet-teeth, as set forth.

In the modified form of construction shown in Fig. 5 the movable head F¹² is pushed along the main or sliding bar A⁸. The latter is provided on its upper edge with teeth A⁹ and throughout its length with the openings A¹⁰. The movable head F¹² is pushed by means of the operating-lever G⁸, which is pivoted by means of the pin G⁹, mounted in one of the openings A¹⁰. The slot F¹³ in the movable head F¹² has its upper wall formed with teeth which engage with the teeth of the bar A⁸. In this modified form of construction shown in Fig. 5 the movable head, as before stated, is pushed by the action of the lever G⁸ instead of being pulled, as shown in Fig. 1.

The ends of the wire are cut and twisted by the tools on the lever G, such as the fork G³, opening G⁵, and cutter G⁷, which is worked by the lever H centering on the fulcrum H'.

It is obvious that the auxiliary head B' may be on the other side of the movable head F, when the lever G will push the movable head F instead of pulling it, thus obviating the necessity for the link F⁸, and the auxiliary head G' may be dispensed with and the movable head pushed, as will be evident with reference to Fig. 5.

The apparatus is operated by the reciprocation of the lever G, which causes a sliding movement to be imparted to the head F, causing the wire to be stretched or strained, or, in other words, drawing one end of the wire

toward the other, and if sufficient wire is now drawn in the ends are twisted up in any of the various ways usually adopted, but if not the end of the wire E is secured each for a moment by the clip A³ and the eccentric and handle D', the clip D is loosened, and the head F moved to the far or outer end of the bar, when the wire is again clipped by the eccentric D, the eccentric D' is opened, and the straining is continued, as has been described.

Having now fully described my invention, what I claim as new, and desire to secure by Letters Patent, is--

In a wire-stretcher, a longitudinally-extending main sliding bar having one end bent in a vertical manner terminating in a horizontally-extending arm with a grooved lower face, a pair of clips secured to said vertically-extending portion of the main bar, a movable head consisting of a vertical member having one side thereof formed with an offset provided with a grooved upper edge, a clip secured to said movable head above the said grooved offset, an auxiliary head mounted upon said main bar, a lever pivoted to the said auxiliary head and adapted to be reciprocated, and suitable connections between the lever and the movable head for causing the operation of the latter when the lever is reciprocated.

THOMAS HEWTON.
